BRUSH HOLDER

George J. Buerosse, Beaver Dam, and Alfred E. Buerosse, Wauwatosa, Wis., assignors of three-fourths to said George J. Buerosse and one-fourth to said Alfred E. Buerosse

Application February 27, 1939, Serial No. 258,778

11 Claims. (Cl. 171—324)

This invention relates to brush holders for dynamoelectric machines.

It is essential in dynamoelectric machines of the type wherein brushes, which are usually of carbon, must be held firmly against commutators or collector rings, that the brushes be held in a manner which will insure the continuance of proper contact between the brushes and the rotating member, and at the same time allow the brush to float to a certain extent so that it will accommodate itself to the surface of the rotating member. Brush holders heretofore in use for this purpose have been more or less complicated in design, and generally of such cumbersome and bulky construction as to preclude their use in small motors.

It is therefore one of the objects of this invention to improve the design and construction of brush holders of the character described with a view toward simplifying their construction and reducing their dimensions.

Another object of this invention is to provide a brush holder of the character described having improved means for gripping the brush per se so as to facilitate changing and adjusting the brushes.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate two complete examples of the physical embodiment of the invention constructed in accordance with the best modes so far devised for the practical application of the principles thereof, and in which:

Figure 1 is a side view of a brush holder constructed in accordance with this invention, and illustrating the manner in which it is installed in use;

Figure 2 is a perspective view of the brush holder;

Figure 3 is a top view thereof;

Figure 4 is a view similar to Figure 1, illustrating a slightly modified embodiment of the invention;

Figure 5 is a side view of the brush holder illustrated in Figure 4, with its parts in their free positions; and

Figure 6 is a top view thereof.

Referring now particularly to the accompanying drawings in which like numerals indicate like parts, the numeral 5 designates a commutator or collector ring of a dynamoelectric machine with which one or more brushes 6 are to be held in engagement. Each brush has its own holder, indicated generally by the numeral 7, which is attached to the outer end of a supporting arm 8 adjustably mounted on a suitable part of the machine.

The holder per se comprises a stationary head 9 and a floating brush supporting head 10 relatively movably connected by a link 11 and a helical spring 12. The stationary head 9 has a split hub 13 adapted to be clamped to a stud 14 carried by the arm 8, and two arms 15 and 16 project in opposite directions from the split head. The former is bifurcated to receive one end of the link 11, and the latter is bored to receive one end of the helical spring 12. The spring 12 fits this bore snugly so that one end of the spring is rigidly connected with the stationary head.

The floating head 10 has a flat outer face 17 against which the brush 6 is clamped by means of a clamping screw 18 threaded in the closed end of a stirrup 19, the side arms of which are pivoted as at 20 to the head 10. At one end, the head 10 is bifurcated like the arm 15 of the stationary head to receive the adjacent end of the link 11, and at its opposite end, the head 10 is bored to snugly receive the spring 12.

The spring 12 has its coils closely wound and is sufficiently stiff to resist lateral flexure thereof with enough force to yieldingly hold the brush in firm engagement with the commutator when the parts are adjusted to flex the spring, as shown in Figure 1.

While this manner of mounting the brush obtains the desired degree of spring tension, it does not preclude the slight motion of the brush necessary to permit the same to seat itself properly on the rotating member, such slight motion being permitted by virtue of the fact that the ends of the link 11 do not fit tightly between the bifurcated arms of the stationary and floating heads, but have a degree of play. It is to be observed, however, that this degree of play is limited, and that the link has a definite guiding action to guide the motion of the floating head.

It is also to be observed that the link and the spring are substantially parallel when the spring is free, as are also the two heads, so that the assembly constitutes substantially a parallelogram to hold the brush at all times parallel to the stationary head.

Attention is also directed to the fact that the novel manner of clamping the brush in place greatly facilitates changing and adjustment of brushes, and that in the event the clamping screw should become slightly loosened, the wedging action incidental to the spring tension acting through a swinging of the stirrup about its pivotal attachment to the floating head maintains the brush firmly clamped to the floating head.

The embodiment of the invention illustrated in Figures 1, 2 and 3 is particularly adapted to small motors, and for larger motors, the construction may be altered to that illustrated in Figures 4, 5 and 6.

In this instance, the stationary head is secured to its supporting stud 14 by means of a set screw 21, and the arms to which the link 11 and the spring 12 are attached are directed rearwardly at an angle so as to compact the assembly by bringing the floating brush supporting head closer to the mounting head.

In other respects, this embodiment of the invention is substantially identical to that described.

From the foregoing description taken in connection with the accompanying drawings, it will be readily apparent to those skilled in the art that this invention provides a brush holder which is extremely simple in design and construction, and which greatly facilitates the application and adjustment of the brushes.

What we claim as our invention is:

1. A brush holder of the character described comprising: a stationary head; a floating brush supporting head; a link pivotally connected to each of said heads to guide the same for relative motion; and a coil spring rigidly connected at its opposite ends to said heads to yieldingly urge the same into predetermined relationship.
2. A brush holder of the character described comprising: a stationary head; a floating brush supporting head; a rigid link pivotally connected at its opposite ends to said heads to guide the heads for relative motion; and a helical spring rigidly connected at its opposite ends to said heads and tending at all times to hold the heads in predetermined relative positions at which the helical spring is straight.
3. A brush holder of the character described comprising: a stationary head; a floating brush supporting head; a substantially rigid pivotal connection between the heads to guide the same for relative motion; and spring means connecting said heads and tending at all times to hold the same in predetermined relative positions.
4. A brush holder of the character described comprising: a stationary head; a floating brush supporting head; a rigid link pivotally connected at its opposite ends to said heads to guide relative motion of the heads; and a helical spring having its opposite ends fixed to said heads to cooperate with the heads and the link in forming substantially a parallelogram so that upon relative motion of the heads they are retained substantially in parallelism.
5. In a brush holder of the character described: a stationary head; a floating brush supporting head; a link pivotally connected at its opposite ends to said heads; and a helical spring having its opposite ends fixed to the heads at points remote from their pivotal connections with the link so that the heads, link and spring form a

quadrilateral figure, and whereby the floating head is at all times yieldingly urged to a predetermined position with respect to the stationary head from which it is movable only by flexing the spring.

6. In a brush holder of the character described: a stationary head having a hub and two oppositely directed arms; a floating brush supporting head; a rigid link pivotally connected at one end to one of the arms of the stationary head and pivotally connected at its opposite end to the brush supporting head; and a helical spring having one end fixed to the opposite arm of the stationary head and its other end fixed to the floating brush supporting head at a distance from its pivotal connection with the rigid link.

7. In a brush holder of the character described: a stationary head; a floating brush supporting head; a link joining said heads to guide the same for relative motion; a helical spring having its opposite ends fixed to the heads and tending to hold the same in relative positions at which the spring is straight; and means for securing a brush to the floating brush supporting head.

8. In a brush holder of the character described: a stationary head; a floating brush supporting head; a link joining said heads to guide the same for relative motion; a helical spring having its opposite ends fixed to the heads and tending to hold the same in relative positions at which the spring is straight; and means for clamping a brush to the floating brush supporting head, said last named means comprising, a stirrup connected to the floating head, and a clamping screw threaded in the stirrup and adapted to clamp a brush against the floating head.

9. In a brush holder of the character described: a stationary head; a floating brush supporting head; means for connecting said heads in a manner allowing relative motion therebetween; including, a helical spring, and a substantially rigid pivotal connection between the heads; a stirrup pivotally connected to the floating head; and a clamping screw threaded in the stirrup and adapted to clamp a brush against the floating head.

10. In a brush holder of the character described: a stationary head; a floating brush supporting head having a substantially flat outer face; means movably connecting said heads including, a helical spring fixed at its opposite ends to the heads; and a substantially rigid pivotal connection between the heads; a stirrup having its arms pivotally joined to the floating head and having its closed end spaced from the flat face of the floating head to receive a brush therebetween; and a clamping screw threaded in the closed end of the stirrup to clamp a brush against the flat face of the floating head.

11. A brush holder of the character described comprising: a stationary head having a hub; spaced arms projecting from the hub and forming a substantially obtuse angle with each other; a floating brush supporting head disposed at that side of the hub opposite the arms; a link pivotally connected at one end to one of said arms and extending across the hub with its opposite end pivotally connected to the floating brush supporting head; and a helical spring having its opposite ends fixed to the other arm and the floating brush supporting head.
